UNITED STATES PATENT OFFICE.

EDWARD T. WILLIAMS, OF BROOKLYN, NEW YORK, ASSIGNOR TO SERVEL, INC., OF NEW YORK, N. Y., A CORPORATION OF DELAWARE.

REFRIGERATION.

Application filed April 25, 1928. Serial No. 272,639.

My invention relates to coolers for drinking water of the type wherein a bottle is inverted on a water container and which is cooled by mechanical refrigerating apparatus.

The objects and advantages of my invention will appear from the following description taken in connection with the accompanying drawing.

On the accompanying drawing, 10 designates generally the water cooler. The water cooler comprises three sections, an upper drinking water section 11, an intermediate machine section 12 and a lower evaporator section 13. The upper section comprises an outer receptacle 14 surrounded by insulation 15, within which is a vessel 16, preferably by glazed earthenware. An inverted bottle 17 is normally placed over vessel 16 to supply drinking water thereto. A severable pipe connection 18 connects vessel 16 with a faucet 19.

In the intermediate machine compartment is a compressor 20 driven by a motor 21 through the intermediary of a belt 22. The compressor serves to compress gaseous refrigerant and discharge it into a condenser 23 which is air cooled by means of a fan 24 driven by motor 21. Refrigerant liquefied in condenser 23 passes through conduit 44 and expansion valve 25 and enters evaporator 26, the discharge end of which is connected to the compressor.

The evaporator comprises a header 27 and a series of loop tubes 28 connected thereto. Inside the header is a float which controls valve 25 to keep a constant level in header 27.

The evaporator is situated within a tank (hereinafter termed brine tank) 29 which is in the lower section of the cooler and which is surrounded by insulating material 30. Set into the brine tank and accessible from outside the cabinet as a whole is a pocket or compartment 31 for holding anything to be chilled. Preferably a drawer 43 is inserted into the pocket for holding material. Such an arrangement may be used to freeze ice cubes in which case the pocket enclosure 31 is arranged in contact with the metal of the evaporator. In such case the arrangement should be so carried out that the liquid in receptacle 14 is not made too cold.

The placing of the evaporator and brine

tank in the lower part of the structure gives stability and makes it possible to keep different temperatures in the evaporator and in receptacle 14 for such different temperature effects as the freezing of water on the one hand and cooling water to pleasant drinking temperature on the other hand.

Brine, which may be pure water or any other liquid which is in liquid form at the operating temperatures, is circulated between brine tank 29 and receptacle 14. Circulation is effected by means of pump 33 which is driven from the motor. Pump 33 is in conduit 34 which connects at one end to the lower part of brine tank 29 and at the other end to receptacle 14 at the bottom thereof and in the vicinity of pipe connection 18. An overflow pipe 35 conducts brine from receptacle 14 back to tank 29. Pipe or conduit 35 extends upwardly into receptacle 14 and determines the level of liquid therein. It is connected to the upper part of tank 29.

Reference character 36 designates an electric circuit for motor 21 which is controlled by a switch 37 in turn controlled by variations in the pressure in conduit 38 connecting the low side header 27 with the suction side of the compressor. When the low side pressure rises above a predetermined value, switch 37 is closed and the compressor is set in motion. When the low side pressure falls below a predetermined value, switch 37 opens the electric circuit to stop the motor and the compressor.

Pump 33 is preferably mounted on the shaft of motor 21 to rotate therewith.

If desired, a valve 40 may be placed in conduit 34 controlled by a thermostat 41 in heat registering relation with liquid of the upper section, as, for example, in contact with vessel 16, and arranged to operate to give a constant temperature in liquid of the upper section. This arrangement would be particularly desirable when using different temperatures.

While I have illustrated and described one form of my invention, it will be understood that variations are possible within the scope of the invention.

Having thus described my invention, what I claim is:

1. A water cooler of the inverted bottle type comprising an upper section, an intermediate section and a lower section, a re-

ceptacle in said upper section, a vessel within said receptacle adapted to hold drinking water, means for removing drinking water from said vessel, mechanical refrigerating apparatus in the intermediate section, a tank in said lower section, an evaporator in said tank connected to said apparatus for flow of refrigerant and serving to cool liquid in said tank, means to circulate liquid between said receptacle and said tank and a drawer in said tank for holding material to be cooled, 55 between said receptacle and said tank.

2. A water cooler of the inverted bottle type comprising an upper section, an intermediate section and a lower section, a receptacle in said upper section, a vessel within 15 said receptacle adapted to hold drinking water, means for removing drinking water from said vessel, mechanical refrigerating apparatus in the intermediate section, a tank in said lower section, an evaporator in said 20 tank connected to said apparatus for flow of refrigerant and serving to cool liquid in said tank and means to circulate liquid between said receptacle and said tank comprising a conduit connected to said tank and connected 25 with said receptacle and so arranged therewith as to determine the level of liquid therein.

3. A water cooler of the inverted bottle type comprising an upper section, an intermediate section and a lower section, a receptacle in said upper section, a vessel within 30 said receptacle adapted to hold drinking water, means for removing drinking water from said vessel, mechanical refrigerating apparatus in the intermediate section, a tank in said lower section, an evaporator in said 35 tank connected to said apparatus for flow of refrigerant and serving to cool liquid in said tank, means to circulate liquid between said 40 receptacle and said tank and a drawer in said tank for holding material to be cooled.

4. A water cooler of the inverted bottle type comprising an upper section, an intermediate section and a lower section, a receptacle in said upper section, a vessel within 45 said receptacle adapted to hold drinking water, means for removing drinking water

from said vessel, mechanical refrigerating apparatus in the intermediate section, a tank in said lower section, an evaporator in said 50 tank connected to said apparatus for flow of refrigerant and serving to cool liquid in said tank, means to circulate liquid between said receptacle and said tank and a drawer in said tank for holding material to be cooled, 55 the arrangement being such that a lower temperature is maintained in said drawer than in said receptacle.

5. A water cooler of the inverted bottle type comprising an upper section, an intermediate section and a lower section, a receptacle in said upper section, a vessel within 60 said receptacle adapted to hold drinking water, means for removing drinking water from said vessel, mechanical refrigerating apparatus in the intermediate section, a tank in said lower section, an evaporator in said 65 tank connected to said apparatus for flow of refrigerant and serving to cool liquid in said tank, means to circulate liquid between said 70 receptacle and said tank and means to control the rate of circulation in response to variations of temperature in the upper section.

6. A water cooler of the inverted bottle 75 type comprising an upper section, an intermediate section and a lower section, a receptacle in said upper section, a vessel within 80 said receptacle adapted to hold drinking water, means for removing drinking water from said vessel, mechanical refrigerating apparatus in the intermediate section comprising a motor, a compressor and a condenser, a tank in said lower section, an evaporator in said tank connected to said 85 apparatus for flow of refrigerant and serving to cool liquid in said tank and means for circulating liquid between said receptacle and said tank comprising a pump mounted co-axially with said motor. 90

In testimony whereof he has affixed his signature.

EDWARD T. WILLIAMS.
